UNITED STATES PATENT OFFICE.

WILLIAM R. THOMAS, OF WATERTOWN, WISCONSIN.

ANTICREEP RAILWAY-RAIL ATTACHMENT.

1,077,377.

Specification of Letters Patent

Patented Nov. 4, 1913.

Application filed April 17, 1913. Serial No. 761,799.

To all whom it may concern:

Be it known that I, WILLIAM R. THOMAS, a citizen of the United States, and resident of Watertown, in the county of Jefferson 5 and State of Wisconsin, have invented certain new and useful Improvements in Anti-creep Railway-Rail Attachments; and I do hereby declare that the following is a full, clear, and exact description thereof.

10 My invention consists in what is herein particularly set forth with reference to the accompanying drawings and pointed out in the claims of this specification, its object being to provide simple, economical, strong, 15 durable, easily applied and efficient anti-creep attachments for railway-rails, the same being an improvement of the one disclosed in my Letters Patent No. 1,034,168, granted July 30, 1912.

20 Figure 1 of the drawings represents a transverse sectional view of my improved anti-creep attachment and a railway-rail to which it is applied, the section being indicated by line 1—1 in the next described 25 illustration; Fig. 2, a plan view of the attachment partly in horizontal section; Fig. 3, a sectional view of said attachment abutting a railway crosstie, the view being indicated by line 3—3 in Fig. 1, and Fig. 4, 30 a side elevation of a notched wedge-block constituting part of the aforesaid attachment.

My improved anti-creep attachment for a railway rail is for the most part a malleable casting member embodying a horizontal plate 5 having a preferably central depending forward stop-flange 6, and a brace-rib 7 between the plate and flange. Rising from one extremity of the plate is a jaw 8 that 35 preferably extends the full width of said plate and is provided upon its inner vertical face with teeth 9, as shown in Fig. 2. Rising from the other extremity of the plate 5 are corner jaws 10, and a web 11 intermediate of said jaws. A slot 12 in the plate 40 is also intermediate of the jaws 10, and the web 11 constitutes the outer wall of the slot.

Projecting from the upper and lower edges of the web 11, central of the same or 45 otherwise suitably disposed, are teeth 13 designed for engagement with rack-notches 14 provided in the outer side of a wedge-block 15 that engages the plate-slot 12 and constitutes another member of the anti-creep 55 attachment herein specified.

The plate and jaws of the malleable cast-

ing member of the attachment are strengthened by means of ribs 16, and in practice said member of said attachment is slipped on a rail 17, the flanges of the rail being 60 caught in said jaws. The stop-flange 6 of the rail-engaging member of the attachment abuts a crosstie 18 of the railway and the wedge-block 15 is engaged with the slot 12 aforesaid in opposition to the adjacent flange of the rail. By driving down the wedge-block the flange of the rail farthest therefrom is forced tight in the jaw 8 and against the teeth 9 thereof, as shown in Fig. 1, after which the teeth 13 aforesaid are 65 bent inward into notches of said wedge block to prevent automatic retraction of the same from any cause. In Fig. 1, one of the teeth 13 is shown engaging a notch of the wedge-block, but the other of said teeth is to 70 be bent inward to engage the adjacent notch of said block and thus complete the union of the two members of the anti-creep attachment in which the rail is firmly gripped, the depending stop-flange of said attachment being opposed by an abutting crosstie 75 that resists the creeping tendency of said rail.

I claim:

1. A railway-rail anti-creep attachment 85 comprising a slotted horizontal plate member having rail-engaging jaw-extremities and a forward depending stop-flange for crosstie abutment, together with a wedge-block member engageable with the plate-slot 90 in opposition to a flange of the rail, and means integral with the plate member for holding the wedge-block member against automatic retraction from adjusted position.

2. A railway-rail anti-creep attachment 95 comprising a slotted horizontal plate member having a depending forward stop-flange for crosstie abutment and said plate provided at its extremities with rail-engaging jaws one of which has a toothed inner face, 100 together with a wedge-block member engaging the plate-slot in opposition to a flange of the rail, and means integral with the plate member for holding the wedge-block member against automatic retraction from ad- 105 justed position.

3. A railway-rail anti-creep attachment comprising a slotted horizontal plate member having a depending forward stop-flange and provided at its extremities with rail- 110 engaging jaws, there being a pair of the jaws and an intermediate web at one extremity

of the plate, said web constituting a wall of the plate-slot and having upper and lower teeth, together with a wedge-block member engageable with said slot and having its 5 outer side rack-notched to be engaged by the aforesaid teeth.

In testimony that I claim the foregoing I

have hereunto set my hand at Milwaukee in the county of Milwaukee and State of Wisconsin in the presence of two witnesses.

WILLIAM R. THOMAS.
